UNITED STATES PATENT OFFICE.

CLARENCE A. MICHEL, OF CLEVELAND, OHIO, ASSIGNOR TO THE GUIDE MOTOR LAMP MANUFACTURING COMPANY, OF CLEVELAND, OHIO, A CORPORATION OF OHIO.

FOCUSING DEVICE FOR AUTOMOBILE LAMPS.

Application filed June 21, 1922. Serial No. 569,876.

To all whom it may concern:

Be it known that I, CLARENCE A. MICHEL, a citizen of the United States, residing at Cleveland, in the county of Cuyahoga and State of Ohio, have invented a certain new and useful Improvement in Focusing Devices for Automobile Lamps, of which the following is a full, clear, and exact description, reference being had to the accompanying drawings.

This invention is a novel construction of device for focusing the incandescent lamp of automobile lamps, the object being to provide a simple and efficient device which will operate to move the socket back and forth in a straight line without tilting.

Heretofore adjustable focusing devices have been made which move the socket back and forth but owing to one inaccuracy or another have the tendency to tilt the lamp up or down, thereby throwing the filament out of focus and it is with the object of avoiding this tilting motion that the present invention has been devised.

The invention consists in the novel features of construction hereinafter fully described and pointed out in the claims.

In the drawings forming a part of this specification—

Figure 1 is a view partly in section and partly in elevation, showing an incandescent lamp and socket together with a portion of the lamp reflector and case and the adjustable focusing device;

Figure 2 is a top plan view of the socket and focusing device connected thereto;

Figure 3 is a section on the line 3—3 of Figure 1;

Figure 4 is a detail perspective view of the rear end of the bar connected to the sleeve of the socket; and

Figure 5 is a detail perspective view of the plate cooperating therewith.

Referring to the drawing A indicates the lamp case, B the reflector therein, C the incandescent lamp which is fitted into the usual construction of socket D and this socket in turn fits within a sleeve E projecting rearwardly from the reflector provided with an offset portion forming a guideway for the purpose hereinafter fully described.

Connected to the socket D at the upper side is a rearwardly extending bar F of

light metal extending into the guideway of the sleeve E so as to prevent the socket from rotating within the sleeve. The rear end of the bar is turned downwardly as shown at F' and this downwardly bent portion has an opening F² cut therein. The bar F fits into the notched portion G' of the plate G and the lower end thereof works between the converging fingers G² and this plate is centrally threaded as shown at G³ into which screws the forward end of the screw H, this screw being projected centrally through the rear end of the casing as most clearly shown in Figure 1.

In practice I prefer to surround the screw by means of a spiral spring I, the forward end of which bears against the plate G while the rear end thereof bears against the interior of the case, the normal tendency of said spring serving to maintain the various parts in their proper assembled positions and prevent vibration.

The downwardly bent end of the bar F is upon the rear side of the plate G and it will be noted that the screw H passes through the opening F² into the threaded opening G³ and this opening F² is considerably larger in diameter than the screw so that in case the screw H should not be exactly in the proper position relatively with the longitudinal axis of the lamp that movement of the lamp forward or backward due to turning the screw will not cause the lamp to tilt up or down inasmuch as the movement of the screw will cause the plate to move back and forth and owing to the loose connection between the bar F and plate G there can be a certain amount of non-alignment between the screw and the longitudinal axis of the lamp and the lamp will be caused to move back and forth in a perfectly true line.

By constructing the plate G in the manner shown, it is obvious that the said plate can have a limited movement up and down and furthermore the notch or recess in the plate into which the bar fits will maintain the socket in the proper position and prevent the same turning and the connection between the bar and plate will also prevent the plate turning, this being accomplished both by the engagement of the bar with the notched or recessed portion and also by the engagement between the depending end and the fingers.

Having thus described my invention, what I claim and desire to secure by Letters Patent is:—

1. In a device of the kind described, the combination with a casing having a reflector provided with a sleeve offset to form a guideway, a socket slidably mounted in said sleeve having an operating bar secured to the side thereof extending into said guideway, said 5 operating bar being provided with an angled apertured rear end, a plate having a notch to receive said bar and oppositely disposed fingers to embrace said bar, said plate being provided with a threaded bore and an adjusting screw carried by the casing working 10 through said apertured bore for adjusting said socket.
2. In a device of the kind described, the combination with a reflector, sleeve, socket, 15 and casing, of a screw working through the casing, a plate through which the forward end of the screw passes, a spring surrounding said screw and bearing against the casing and plate, a bar connected to said socket, the rear end of said bar being angled and apertured, said angled end of the bar engaging the plate, said plate being notched to re-

ceive said bar and provided with fingers to embrace said bar, the aperture in the end of the bar being larger than the diameter of the screw whereby a loose connection between the plate and bar is obtained. 20

3. A lamp comprising a casing having a reflector provided with a horizontally disposed sleeve offset to form a longitudinal guideway, a socket slidably mounted within said sleeve having a bar secured to the side thereof extending into said guideway for preventing said socket from rotating within said sleeve, said bar extending rearwardly 25 and provided with a depending angled apertured end, a plate having a notch to receive the horizontal portion of said bar and provided with fingers to embrace the depending end thereof, said plate having a threaded bore, a screw mounted in said casing extending through the aperture of said bar and working in the threaded bore of said plate for adjusting said socket within said sleeve 30 and a coiled spring disposed between said casing and the depending end of said bar. 35

In testimony whereof, I hereunto affix my signature.

CLARENCE A. MICHEL.
